FREQUENCY CONVERTING CIRCUIT WITH MIXING ELEMENT IN INPUT CIRCUIT OF AMPLIFYING DEVICE

Edward Herman Hugenholtz, Toronto, Ontario, Canada, assignor to North American Philips Company, Inc., New York, N.Y., a corporation of Delaware

Filed Nov. 10, 1959, Ser. No. 852,654

7 Claims. (Cl. 325—440)

The invention relates to a frequency converting circuit arrangement comprising a mixing element and a self-oscillating electronic amplifying device. It has for its object to provide an improvement in gain and stability over that found in self-oscillating mixer circuits.

Self-oscillating mixer circuits are frequency converter circuits in which the mixing and oscillation functions are achieved by the same amplifying device, such as an electron tube or transistor. Although self-oscillating mixing circuits provide economy of space and components, they also provide several disadvantages. Since the input circuit is connected to an oscillating electronic amplifying device in a self-oscillating mixer, radiation of the oscillating signal at the given or local oscillator frequency through the input circuit may exceed tolerable limits and as a result, special filtering may be required.

Another disadvantage of self-oscillating mixer circuits is the low gain of the electronic amplifying device which is a result of the biasing or operating point at which the electronic amplifying device is set to permit it to mix satisfactorily. In addition, the input circuit of the electronic amplifying device provides high damping of a signal at a high value of radio frequency, which further reduces the gain of the system.

A further disadvantage of self-oscillating mixer circuits is the tendency for the oscillations of the local oscillator to be pulled or blocked entirely by a strong input radio frequency signal. Blocking or frequency pulling of the local oscillator is particularly noticeable when a receiver employing a self-oscillating mixer circuit is tuned to a weak or distant station with a strong local station occupying the adjacent channel.

Self-oscillating mixers generally exhibit a tendency towards instability of the local oscillator when the tuned circuit for the input radio frequency signal is varied. This is due to the inherent coupling of the tuned circuit for the input signal and the tuned circuit for the local oscillator.

In order to prevent positive or negative feedback of the intermediate frequency and still permit amplification at this frequency, it has been generally necessary to employ an oscillator which utilized a frequency determining circuit which compels the oscillator to oscillate at the given frequency connected between the output and input of the electronic amplifying device or between plate and grid, when a tube is used as the electronic amplifying device, in order to permit the signal at the second value of frequency to be connected to the input or grid, and yet not have the amplified signal at the second value of frequency at the plate fed back through the given frequency circuit to the grid. When a circuit is connected between the input and output of the electronic amplifying device, a greater interaction of the input and output tuned circuits takes place, making the individual adjustment of any one of these circuits difficult.

The frequency converting arrangement according to this invention mitigates the previously mentioned disadvantages of self-oscillating mixer circuits by carrying out the mixing process in a separate mixing element located in the input circuit of the electronic amplifying device. In this arrangement the amplifying device is adapted to oscillate at the local oscillation frequency, the local oscil-

2

lations being coupled to the mixing element. The input radio frequency signal is also coupled to the mixing element where it is mixed with the signal at the given frequency to produce the intermediate frequency signal.

5 The intermediate frequency signal is coupled back to the electronic amplifying device and is amplified in this device. A special advantage possible with this arrangement is that the oscillator frequency determining circuit is located totally in the input circuit of the electronic amplifying device, eliminating the output to input local oscillation frequency determining circuit.

Since the mixing element may be a vacuum diode with a separate cathode contained in the same envelope as the electronic amplifying device when a tube is employed or

15 a simple semiconductor diode when either a tube or a transistor is employed as the amplifying device, the increase in cost is low and the added space required is extremely small. Therefore, the basic advantages of the self-oscillating mixer, which are the use of few components and low cost, are maintained.

20 The separate mixing element in this invention provides a separation of the signal at the given frequency from the input circuit and thus reduces radiation of this signal. The higher mixing efficiency of this separate mixing element and the higher amplification of the electronic amplifying device when it is not biased to mix provide a greater overall gain. In addition, the electronic amplifying device provides less damping to the lower intermediate frequencies and therefore provides an even greater gain.

25 30 Due to the separation of the circuit containing the oscillations of the local oscillator frequency and the electronic amplifying device provided by the separate mixing element, frequency pulling and blocking of the oscillator is substantially reduced. In addition, this separation also enhances the stability of the oscillator as the tuning circuit for the oscillator is varied.

35 Since the local oscillator frequency determining circuit is located totally in the input circuit of electronic amplifying device, adjustment of the tuned circuits in the output and input of the electronic amplifying device will have less effect on each other and thus facilitate their individual tuning.

40 45 In order that the invention may be readily carried into effect, it will now be described in greater detail with reference to the accompanying drawing, in which:

FIG. 1 is a block diagram of a frequency converting circuit according to the invention;

FIG. 2 is a circuit diagram illustrating one embodiment of the invention;

FIG. 3 is a circuit diagram of a portion of the circuit of FIG. 2 illustrated as a bridge circuit;

FIG. 4 is a circuit diagram illustrating another embodiment of the invention;

FIG. 5 is a circuit diagram of a portion of the circuit of FIG. 4 illustrated as a bridge circuit;

FIG. 6 is a circuit diagram of still another embodiment of the invention; and

FIG. 7 is a circuit diagram of a portion of the circuit of FIG. 6 illustrated as a bridge circuit.

50 55 60 65 70 75 80 85 FIG. 1 shows a block diagram of the invention in which the input terminals 10 of the mixing element 11 receive the input radio frequency signals. The electronic amplifying device 12, which is adapted to oscillate at a given frequency, is coupled to the mixing element 11 through coupling 13 to permit the signal at the given frequency to be conveyed to the mixing element 11 where it mixes with the input radio frequency signals to produce the intermediate frequency signals. The intermediate frequency signals are coupled to the electronic amplifying device 12 through the coupling 13. The amplified intermediate frequency signals are derived at the output terminals 14 of the electronic amplifying device 12.

FIG. 2 illustrates an embodiment of the invention which employs a semiconductor diode D_1 as the mixing element and a vacuum tube triode T_1 as the electronic amplifying device. In this circuit the radio frequency signal is coupled from inductor L_1 to inductor L_2 . L_2 and C_3 are resonant at the frequency of the input signals and the radio frequency signals are impressed on semiconductor diode D_1 . Inductor L_4 in conjunction with the triode T_1 and capacitors C_6 , C_7 , C_8 and the input capacity of T_1 form a Colpitts oscillator which is adapted to oscillate at a given frequency. Since the oscillator oscillations are generated across the inductor L_4 , they are also impressed on diode D_1 through capacitor C_5 . The inductor L_3 in conjunction with C_6 , C_7 , C_8 and the input capacity of the triode T_1 form a resonant circuit at the intermediate frequency.

FIG. 3 illustrates a portion of the circuit of FIG. 2 as a bridge circuit, wherein the alternating component of cathode current is fed around inductor L_3 through two paths. The first path is through C_7 and C_8 and the second is through $C_6 + C_{6K}$ and $C_5 + L_4$. $C_5 + L_4$ form at the intermediate frequency an effective capacitance designated C_5' . The ratio of $C_6 + C_{6K}$ to C_5' is equal to the ratio of C_7 to C_8 . In this way, the cathode current forms no feedback voltage across L_3 and, therefore, the electronic amplifying device does not oscillate at the intermediate frequency. C_9 has the function in this circuit of neutralizing the plate to grid capacity C_{pg} .

Although the bridge circuit prevents oscillation at the intermediate frequency, the signal of the intermediate frequency is coupled through the direct current blocking condenser C_4 to the grid of the electronic amplifying device wherein it is amplified and derived at the tuned circuit comprised of L_5 , C_{10} and the output capacity of T_1 . The amplified version of the signal at the intermediate frequency is coupled from L_5 to input of the next stage which is comprised of L_6 and C_{13} .

In this circuit, R_1 serves as a direct current return for the diode D_1 . R_2 serves as a direct current return for the grid of T_1 . R_3 serves in place of a choke to maintain the cathode of T_1 at an alternating potential above ground. R_4 serves to de-couple the direct current plate supply voltage for T_1 . C_{11} and C_{12} serve to place the lower connections of L_5 and L_6 at alternating current ground.

Purely by way of illustration and in no sense by way of limitation, the following circuit component values may be employed in the circuit of FIG. 2:

Capacitor C_3	4.7 μf .
Capacitor C_4	1000 μf .
Capacitor C_5	6.8 μf .
Capacitor C_6	4 μf .
Capacitor C_7	6.8 μf .
Capacitor C_8	10 μf .
Capacitor C_9	1 μf .
Capacitor C_{10}	10 μf .
Capacitor C_{11}	1000 μf .
Capacitor C_{12}	120 μf .
Capacitor C_{13}	10 μf .
Resistor R_1	15K ohms.
Resistor R_2	100K ohms.
Resistor R_3	1500 ohms.
Device T_1	Tube 6ER5.
Device D_1	Germanium diode 1N87A.
Inductor L_1	1.7 μh .
Inductor L_2	1.5 μh .
Inductor L_3	1.1 μh .
Inductor L_4	0.4 μh .
Inductor L_5	1.1 μh .

FIG. 4 illustrates a frequency converter which utilizes two diodes in a balanced mixer circuit, and a pentode in the oscillator-amplifier circuit. Inductor L_1 couples the radio frequency signal to the semiconductor diodes D_2 and D_3 through inductor L_2 . Inductor L_4 in conjunction

with capacitors C_{17} , C_{14} , C_{16} , C_{18} , C_{15} and C_{19} and pentode T_2 form an oscillator at a given frequency. The signal at the given frequency across L_4 is coupled to the diodes through capacitors C_{17} and C_{18} where it mixes the input signal to produce the intermediate frequency which is impressed across a circuit tuned to this frequency and composed of inductor L_3 in conjunction with capacitors C_{17} , C_{18} , C_{14} , C_{15} and C_{16} . The intermediate frequency signal across inductor L_3 is coupled through the direct current blocking capacitor C_{14} to the control grid of the pentode T_2 where it is amplified.

The amplified version of the intermediate frequency signal is derived across the plate tuned circuit comprised principally of inductor L_5 , capacitor C_{20} and the output capacity of tube T_2 . The amplified intermediate frequency signal is coupled from inductor L_5 to inductor L_6 . Inductor L_6 , capacitor C_{23} and the input capacity of the amplifying device of the next stage form the input tuned circuit at the intermediate frequency for the next stage.

20 The bridge circuit of FIG. 5 is a portion of the circuit of FIG. 4 in bridge form. This circuit illustrates the means by which oscillation at the intermediate frequency is prevented. The ratio of capacitor C_{15} to capacitor C_{18} is chosen equal to the ratio of capacitor C_{16} to capacitor C_{17} . In this way no intermediate frequency component of the cathode current is impressed across inductor L_3 and therefore there is no feedback at the intermediate frequency.

25 FIG. 6 illustrates a modification of the frequency converter of FIG. 2, utilizing a transistor S_1 as the electronic amplifying device and a semiconductor diode D_1 as the mixing element. FIG. 7 illustrates the bridge circuit of the circuit of FIG. 6, which prevents oscillation at the intermediate frequency. The principle of operation of the circuit of FIGS. 6 and 7 is identical to that of FIGS. 2 and 3 with the exception of the standard biasing arrangement required for the transistor.

30 While the invention has been described by means of specific examples and in specific embodiments, I do not wish to be limited thereto, for obvious modifications will occur to those skilled in the art without departing from the spirit and scope of the invention.

35 What I claim is:

1. A frequency converting circuit comprising an amplifying device having at least an input electrode, a common electrode, and an output electrode, a point of reference potential, tuned circuit means connected between said input electrode and said point of reference potential, means respectively connecting said common electrode to said tuned circuit whereby local oscillations are generated, 40 a source of high frequency oscillations, a mixing device having first and second terminals, means connecting said source between said first terminal and said point of reference potential, means connecting said second terminal to said input electrode whereby said high frequency oscillations and local oscillations are mixed in said mixing device to provide oscillations of an intermediate frequency and said intermediate frequency oscillations are applied to said input electrode, and output circuit means connected to said output electrode to derive amplified intermediate frequency oscillations therefrom.

2. The circuit of claim 1 in which said mixing device comprises a pair of diodes connected in a balanced circuit.

3. The circuit of claim 1 in which said amplifying device is an electron discharge tube.

4. The circuit of claim 1 in which said amplifying device is a transistor having base, emitter and collector electrodes, said input, common and output electrodes comprising said base, emitter and collector electrodes, respectively.

5. A frequency converting circuit comprising an electron discharge tube having cathode, control grid, and anode electrodes, impedance means connecting said cathode to ground, a local oscillation frequency determining circuit regeneratively connected to said tube for providing

ing local oscillations comprising first and second serially connected capacitors connected in parallel with first inductance means between said control grid and ground, and means connecting the junction of said capacitors to said cathode, a source of high frequency oscillations, a diode mixing device, means applying said high frequency oscillations to said mixing device, and means connecting said mixing device to said control grid electrode whereby said local oscillations and high frequency oscillations are mixed in said mixing device to provide intermediate oscillations, and said intermediate oscillations are applied to the control grid electrode of said discharge tube.

6. A frequency converting circuit comprising an electron discharge tube having cathode, control grid, and anode electrodes, impedance means connecting said cathode to ground, a local oscillation frequency determining circuit regeneratively connected to said tube for providing local oscillations comprising first, second and third serially connected capacitors connected in parallel with first inductance means between said control grid and ground, means connecting the junction of said first and second capacitors to said cathode, intermediate frequency determining means non-regeneratively connected to said tube comprising second inductance means connected in parallel with said first and second capacitors, a fourth capacitor, means serially connecting said fourth capacitor and third capacitor in parallel with said second inductor, neutralizing capacitor means connected between said anode and the junction of said second and third capacitors, a source of high frequency oscillations, a diode mixing device, means applying said high frequency oscillations to said mixing device, and means connecting said

10
15
20
25
30

mixing device to said control grid electrode whereby said local oscillations and high frequency oscillations are mixed in said mixing device to provide intermediate oscillations, and said intermediate oscillations are applied to the control grid electrode of said discharge tube.

7. A frequency converting circuit comprising an amplifying device having at least an input electrode, an output electrode, and a common electrode, a source of high frequency oscillations, diode means having first and second terminals, first tuned circuit means connected between said input electrode and a point of reference potential, second tuned circuit means connected between said input electrode and point of reference potential, bridge means connecting said common electrode to said first and second tuned circuits to provide self-generated local oscillations of the frequency of said first tuned circuit and to prevent self-oscillations at the frequency of said second tuned circuit, means connecting said source of high frequency oscillations between said first terminal and said point of reference potential, means connecting said second terminal to said input electrode whereby said high frequency and local oscillations are mixed in said diode means to produce intermediate frequency oscillations that are applied to said second tuned circuit and input electrode, said second tuned circuit being tuned to the frequency of said intermediate oscillations, and output circuit means for deriving amplified intermediate frequency oscillations from said output electrode.
